ROOFING TILE

Wilhelm Ludowici, Jockgrim/Pfalz, Germany

Application March 16, 1933, Serial No. 661,193
In Germany April 23, 1932

2 Claims. (Cl. 108—10)

This invention relates to roofing tiles, and has for its object to provide a dovetailed tile by which a waterproof and light-tight roof may be constructed. An interlocking roofing tile according to the invention comprises one or more head ribs, an underneath bottom closing rib set back from the bottom edge of the tile and adapted to engage with a head rib of the next lower tile, an upwardly directed rib running along or adjacent to one side edge of the tile and forming the boundary wall of a main water trough, said boundary wall having a longitudinal groove in its upper surface constituting an auxiliary water trough, and a pair of underneath side closing ribs one running along or adjacent to the side edge of the tile opposite to that having the troughs and adapted to engage with the main trough of an adjacent tile while the other side rib is parallel to the first and set back from the edge of the tile and adapted to engage in the auxiliary water trough of the adjacent tile.

The invention will now be more clearly understood with reference to the accompanying drawings which illustrates by way of example two forms of the invention.

In the drawing wherein like references denote like or similar parts:

Fig. 1 is a top plan view;

Fig. 2 is a plan view of Fig. 1 when turned about its right hand longitudinal edge and shows the underneath of the tile;

Fig. 3 is a section along the line 3—3 of Fig. 1 and showing the tile interlocking with adjacent tiles as when in position on the roof;

Fig. 3A is a view to an enlarged scale of part of Fig. 3 showing the interlocking of the side ribs.

Fig. 4 is a cross section along the line 4—4 of Fig. 2;

Fig. 5 is an enlarged partial cross section along the line 5—5 of Fig. 1;

Fig. 6 is a top plan view of a roofing tile according to the invention with an alternative form of rib, and

Fig. 7 is a plan view of Fig. 6 when turned about its right hand longitudinal edge and shows the underneath of the tile.

The tile according to the invention consists of a flat or almost flat plate *i*, having a bottom portion and a side portion, (right hand of Fig. 1) both of which portions overlap the tile underneath to a considerable extent. The lower end or bottom portion of the plate *i* is bent downwards, as shown in Fig. 4, preferably so that its surface forms an obtuse angle to the main sur-

face of the tile which is substantially flat; whereby when one tile is laid upon the other the angle turned through when passing from the curved portion of the upper tile on to the main surface of the lower tile is also obtuse. The extremity of the lower end may be constituted by a rib *n* substantially normal to the plane of the plate *i*. This form of construction not only gives the whole roof a pleasing and quiet appearance, but has the further advantage of giving the water a rapid flow off, because the curved surface of the lower end will quickly drain the water off the surface *i* so that any penetration of water below the end of the tile is not possible, as in the case of ordinary straight edged tiles.

When the tiles are laid together they dovetail as is shown in Fig. 3 in cross section. The water conduit consists of a main trough *b* having a boundary wall along the top edge of which extends a groove constituting an auxiliary trough *b*1, so that the water flowing off the tile through trough *b* cannot penetrate into the building over the left edge of the tile in Figs. 1 and 3. This closure wall extends upwardly to the under surface of the overlapping side portion of the adjacent tile. At the right hand edge of the tile as seen in Figs. 1 and 3 is provided a pair of underneath closing ribs *c* and *a*, of which the rib *c* runs along or adjacent to the side edge of the tile opposite to that having the troughs, and is adapted to engage with the main trough *b* of an adjacent tile, while the other rib *a* is parallel to the rib *c* and set back from the edge of the tile and adapted to engage in the auxiliary water trough *b*1 of the adjacent tile. The adjacent tile is so constructed that the closing rib *a* forms a line closure therewith, further the inner portion *c*1 of the boundary wall of the trough *b* is lower than the outer portion, the whole constituting a construction which shuts out light or soot and the like. The shape of the rib *c* permits the water to flow freely.

The dovetailing at the top end of the tile consists of a main rib *e* and a rib *f*, both on the upper surface of the tile. On the under surface of the tile at the lower end is a closing rib *g* which is set back from the rib *n* and rests against the rib *f* of an adjacent tile when laid, the rib *g* having notches *h* in which projections *h*1 and *h*2 of the adjacent tile engage. Thus when four tiles are laid together, they will be given the usual stagger as is shown in Fig. 3. There are two oblique openings *f*1 in the closing rib *f* through which openings *f*1 the water accumulating at the head of the tile is led on to the flat surface thereof.

In addition to the rib h_2 there is provided a further rib h_3 , both ribs h_2 and h_3 preventing the water from coming out where adjacent tiles abut.

On the underside of the tile there is provided a longitudinal waveshaped rib k having a hole o_1 for tying purposes, a similar hole o_2 being provided in a cross rib l at the lower end of the tile. By providing the rib k , warping of the tile during manufacture, especially while drying and furnacing, is prevented and moreover the rib k forms a reinforcement to take any strains that might occur while laying the tiles.

The lateral edges of the lower extremity n of the tile are provided with notches m on the under-
15 side so that water can drip off more easily, the extremity n being somewhat thicker at the lateral edges to accommodate the notches. At the top end of the tile on the underside thereof is provided a rib p by which the tiles may be hung from
20 the laths.

As shown in Fig. 5, the bottom of the main trough b inclines downwardly as indicated at x towards the middle of the tile, so that water running down the trough is prevented from over-
25 flowing the edges.

Sometimes the laths of the roof are not accurately placed, and to permit adjustment longitudinally of the tiles to compensate for the inaccuracies, the shape of the ribs at the top and bottom ends may be modified as shown in Figs.
30 6 and 7.

To this end the upper head rib e is made somewhat thinner at e_1 and the closing rib f is similarly reduced at f_2 and slightly curved. By this means the distance between the ribs c_1 and f_2 is made greater than that between the ribs e_1 and f in Fig. 1 so that the overlying tile can be moved longitudinally for adjustment of position to a greater extent than in the case of the tile shown in Fig. 1. Correspondingly, the lower extremity or rib n and the rib g above it, are carried through to the edge of the tile in a somewhat curved shape. Finally the lower end of the watertrough b may be notched at the lower end b_2 —see Fig. 6—to facilitate the discharge of water from the trough.

As a result of the curving of the ribs g and n on the underside of the tile, it is possible to carry

the rib c to the end of the rib n . In this way the watertrough is shut off completely to the edge of the tile, while the rib a is somewhat shorter. By these means a better interlock is secured at the head of the tile, and the head receives at this spot a reinforcement, which is an advantage when drying the tile.

What I claim is:—

1. An interlocking roofing tile having an upwardly directed rib running along or adjacent to one side edge of the tile and forming the boundary wall of a main water trough, said boundary wall having a longitudinal groove constituting an auxiliary water trough in its upper surface of a depth such that the bottom of said groove is 15 higher than the bottom of the main water trough, each of said main and auxiliary water troughs having an independent outlet passage for water, and a pair of underneath side closing ribs, one running along or adjacent to the side edge of the 20 tile opposite to that having the troughs and adapted to engage with the main trough of an auxiliary tile while the other side rib is parallel to the first and set back from the edge of the tile and adapted to engage in the auxiliary water 25 trough of the adjacent tile.

2. An interlocking roofing tile having an upwardly directed rib running along or adjacent to one side edge of the tile and forming the boundary wall of a main water trough, said boundary 30 wall having a longitudinal groove constituting an auxiliary water trough in its upper surface of a depth such that the bottom of said groove is higher than the bottom of the main water trough, each of said main and auxiliary water troughs 35 having an independent outlet passage for water, and a pair of underneath side closing ribs, one running along or adjacent to the side edge of the tile opposite to that having the troughs and adapted to engage with the main trough of an 40 auxiliary tile while the other side rib is parallel to the first and set back from the edge of the tile and adapted to engage in the auxiliary water 45 trough of the adjacent tile, said other side rib being dimensioned relatively to the auxiliary trough so as not to fill it and being shaped to make line contact with the overlying tile.
